United States Patent Office

Des. 187,925
Patented May 17, 1960

187,925

LOUD-SPEAKER CABINET

Edward F. Shaver and Ralph P. Glover, La Grange Park, Ill., assignors to The Muter Company (Jensen Manufacturing Company Division), Chicago, Ill., a corporation of Illinois

Application April 27, 1959, Serial No. 55,673

Term of patent 14 years

(Cl. D26—14)

Fig. 1 is a perspective view of a loud-speaker cabinet showing our new design; and

Fig. 2 is a side elevational view, the opposite side being substantially a mirror image thereof.

We claim:

The ornamental design for a loud-speaker cabinet, substantially as shown and described.
